CLAIM

The ornamental design for a high heel protector, as shown and described.

DESCRIPTION

FIG. 1 is an enlarged top and right front perspective view of a high heel protector showing my new design.

FIG. 2 is a front elevational view thereof;

FIG. 3 is a rear elevational view thereof;

FIG. 4 is a right side elevational view thereof, the left side being a mirror image thereto.

FIG. 5 is a top plan view thereof; and

FIG. 6 is a bottom plan view thereof.

FIG. 6**FIG. 2****FIG.3****FIG.4**
